UNITED STATES PATENT OFFICE.

CARL H. HALLAUER, OF LOS ANGELES, CALIFORNIA.

CHARGE-FORMING DEVICE.

Application filed November 8, 1921. Serial No. 512,485.

To all whom it may concern:

Be it known that I, CARL H. HALLAUER, a citizen of the United States, residing at Los Angeles, in the county of Los Angeles and State of California, have invented new and useful Improvements in Charge-Forming Devices, of which the following is a specification.

My invention relates to the heating, carbureting and feeding of explosive vapors to internal combustion engines and more specifically to the manifolds connecting the carburetor and engine and also pertains to a means for delivering a supply of heated air to the carburetor, and heated or cold air to the intake manifold.

An object of my invention is to make a throttle valve adapted to have variable openings to control the temperature of the fuel mixture by means of changing the openings of the throttle valve to suit the needs of the engine.

To obtain a comparatively high temperature of the fuel mixture at light loads and a lower temperature at heavy loads.

Another object is to provide means for selecting the amount of fuel required in relation to the volume of air necessary in either a cold state, or a hot state, and variations of the same, and at times the use of both hot and cold air to be added to the constantly heated mixture from the carburetor.

A further object is to provide a multiple throttle valve housing, connected with the heated chamber of the exhaust manifold and also connected to the carburetor inlet manifold and adapted to have a multiple valve mounted therein, to connect the various leads respectively thereto, and therefrom the carburetor and internal combustion engine to obtain the proper fuel mixture necessary therefor, causing heated air to pass through the carburetor to the exclusion of cold air, with means to enable an operator to selectively cause a change of temperature according to the work to be performed by an internal combustion engine.

A still further object is to provide means whereby the air inlet and the mixture outlet pipes to and from the carburetor may be heated at all times to prevent condensation of the mixed gas supply to the engine when it is in operation.

Other objects will appear hereinafter.

The invention is illustrated in the accompanying drawings in which:

Fig. 1 is a fragmentary side elevation of an internal combustion engine, showing the intake and exhaust manifold and the carburetor with connections. 60

Fig. 2 is a sectional view partly in elevation taken on the lines 2—2 of Fig. 1.

Fig. 3 is a part sectional and elevational view taken on the same plane as Fig. 1, to clearly show the exhaust manifold with the air heating pipe mounted therein. 65

Fig. 4 is a view partly in section and partly in elevation taken on the line 4—4 in Fig. 1. 70

Fig. 5 is a sectional view taken substantially on the lines 5—5 of Figs. 2 and 4.

Fig. 6 is a projected diagram of the side of the throttle valve housing. 75

Fig. 7 is a projected diagram of the inside of the throttle valve cylinder.

Figs. 8, 9, 10, 11, 12, 13 and 14 are assembled projected diagrams illustrating the various positions in which the throttle valve will be used in the distribution of the fuel mixture with hot and cold air. These views are for the purpose of clearly showing the valve operation. 80

Having described the views, I now refer to the drawings in which like parts will be identified by like numbers. 85

More specifically 1 indicates an internal combustion engine on which is mounted an exhaust manifold 2, and a carburetor intake manifold 3. Connected to the exhaust manifold 2, and the carburetor intake manifold 3, is a throttle valve housing 4, in which is mounted a multiple throttle valve 5. A cap screw 6 fastens the upper portion 7 of the valve housing 4 to the exhaust manifold 2, and a cap screw 8 connects the lower portion 9 of the valve housing 4 to the intake manifold 3. The exhaust manifold 2 has a shell 10 cast upon its upper side, having an air space 11, traversing the full length of the shell 10, being open at either end so that the top of the exhaust manifold 2 and the shell 10, being integrally cast form a hot air passageway. 95

Mounted in an exhaust manifold 2, is a hot air tube 12, which is held fast by acting as a metal core when casting the exhaust manifold 2. Its intake end is placed centrally from either end of the exhaust 110

manifold 2, as designated by numeral 13, and projects a slight distance and opens above the upper wall of the exhaust manifold. The tube is formed with a straight portion 14, extending rearwardly in the manifold to a bend 15 and then extending downwardly to a right angle bend 16 and passes through and beyond the lower wall 17 of the exhaust manifold. The end of the tube is threaded to receive a union nut 19, and is fixed as at 18 in the lower wall 17 of the exhaust manifold 2. Thus I have fixed a metal tube 12 in the exhaust manifold 2 for the purpose of leading hot air direct to the carburetor mixing chamber.

The union nut 19 connects a carburetor inlet pipe 20 to the hot air tube 12. Fixed to the pipe 20 is a carburetor 21 having an outlet pipe 22. The lower connection of said pipe 22 is connected to the carburetor 21 by means of a flange connection 23. The pipe 22 extends upwardly and is fixed by means of a union nut 24 to a spout 25 cast on the throttle valve housing 4.

In the upper portion 7 of the valve housing is a hot air conduit 26 and in the side of a shell 10 is the shell conduit 27. These two conduits communicate and form a hot air passage from the air space 11 directly to the throttle valve 5. A cold air inlet opening 28 is formed at the top of the throttle valve housing 4. The throttle valve 5 has an irregular shaped hot air inlet opening 29 near the upper side, connecting the opening 26 or the opening 28 with the throttle valve chamber 30. The irregular shaped opening 29 will be described later in detail; the purpose of which, is for the admittance of hot air, cold air or both to the chamber 30, in variable amounts. An air and fuel mixture outlet opening 31, is formed on the lower side of the throttle valve 5, connecting the chamber 30 to an air and fuel mixture conduit in the lower portion 9 of the throttle valve 4, also there is a fuel mixture inlet opening 33 about the middle of the outside of the valve to connect the spout 25 and the throttle valve chamber 30.

The throttle valve housing 4 has a screw threaded cap 34 on one end and a screw threaded cap 35 on the other end, the purpose of which, is to enclose the throttle valve 5 in the housing 4. A pintle 36 projects from the end wall 37 of the throttle valve 5 on one end, and a stub shaft 38 projects from the wall 39 on the other end of the throttle valve 5. Mounted and fixed on this shaft 38 is a control lever 40 adapted to receive connections (not shown) for manually operating the throttle valve 5. The caps 34 and 35 act as bearings for the valve cylinder 5.

The mixture inlet opening 41 of the intake manifold 3 is shown in Fig. 2 in connection with the engine intake valve open-

ing 42 in the engine 1, and the exhaust outlet opening 43 is shown in Fig. 2 as connecting the exhaust valve opening 44 in the engine 1.

Referring to Fig. 6, illustrating the valve housing in diagram, the various openings are indicated as follows: 26 designates the hot air conduit, 28 the cold air inlet opening, 25 the fuel mixture spout and 32 the air and mixture conduit.

Referring to Fig. 7, illustrating the throttle valve cylinder in diagram, the various openings are designated as follows: 29 indicates the irregular shaped opening, 33 the fuel mixture opening and 31 indicates the air and fuel mixture outlet opening.

In Fig. 8 is shown the normal position of the valve cylinder 5 when the engine is idling or doing very light work.

The irregular shaped hot air inlet opening 29 is a distorted hexagonal opening in the wall of the valve cylinder 5. While the irregular shaped hot air inlet opening 29 is changing the volume of hot and cold air it will be seen that the spout opening 25 is gradually increased and will attain its full area in the last stage shown in Fig 14, and that the air and mixture conduit opening 32 will increase to its full area shown in Fig. 11, and remain so until the full area of the spout opening 25 is reached in Fig. 14.

Assuming a progressive rotation of the valve 5 is used, in the direction of the arrow 45 in Figs. 8 to 14 inclusively, an understanding will be had of the functioning of the irregular shaped hot air inlet opening 29. First the valve 5 is rotated as shown in Fig. 9 until the point 46 of the irregular shaped hot air inlet opening 29 uncovers the hot air conduit opening 26 near its transverse center and reaches the edge 47 of the hot air conduit opening 26, thereby forming a narrow triangular opening registering with the rectangular hot air conduit opening 26. It will be seen that the movement in either direction of the valve 5 will change the area of the hot air conduit opening 26 and the volume of hot air admitted to the combustion chamber 30.

Rotating the valve cylinder 5 so that the point 46 reaches the edge of the cold air opening as shown in Fig. 10, will increase the hot air conduit opening 26 to its full area.

Rotation of the valve 5 until the point 46 uncovers the cold air inlet opening 28 as shown in Fig. 11, will form a triangular opening for the admittance of cold air. It is now seen that there is a full opening for the hot air and a partial opening for the cold air to the valve chamber 30. Rotating the valve 5 until the hot air conduit opening 26 is partially closed the point 49 will be in alignment with the edge 50 of the hot

air conduit opening 26 and at the same time increasing the cold air inlet opening 28 as shown in Fig. 12. Rotating the valve 5 until the point 49 reaches the edge 47, the hot air conduit opening 26 will be entirely closed, thereby shutting off the hot air and increasing the cold air inlet opening 28 whereby a greater amount of cold air will be admitted to the combustion chamber 30, 10 as shown in Fig. 13. Rotating the valve 5 to its last position as shown in Fig. 14, the point 46 will be in alignment with the line 51 and the point 49 will be in alignment with the line 48 at which position a full opening of 15 the openings 29 is obtained for the admission of cold air, and likewise the spout opening 25 and the air and mixture conduit opening 32 respectively will be fully opened through the valve openings 33 and 31 for the admittance of a fuel mixture to the valve chamber 20 37 and the discharge of the mixed gases through the air and mixture conduit 32 the intake manifold 3, then to the engine intake valve opening 42.

25 As described the hot air tube 12 will become heated by the engine exhaust by reason of its position in the exhaust manifold 2 so that any air drawn through the tube 12 will be heated and due to the construction shown 30 must necessarily pass into the carburetor mixing chamber in a heated condition thereby heating the atomized raw fuel and converting the atomized explosive fuel into a dry rich gaseous explosive mixture so that 35 the mixture passing into the engine will have a greater explosive force. As the carburetor air leads will be heated while the engine is operating, condensation will be practically eliminated. This multiple valve 40 acts as a compensating device for the engine in using an explosive fuel mixture that may at times be composed of part hot air passing through the carburetor with an added supply of more hot air or 45 with part hot air and some cold air or with all cold air combined with the heated fuel mixture from the carburetor.

50 By the operation of the valve to change and vary the several openings almost any desirable result can be obtained to better enable an internal combustion engine to perform more efficiently, economically and with more power than at present obtained in this type of engine.

55 While I have shown and described a specific embodiment of my invention, I do not limit myself to the exact details of construction shown, but may resort to such changes and modifications as occasion may 60 require coming within the scope of the appended claims.

What I claim is:

1. A charge-forming device comprising an exhaust manifold a shell mounted upon said exhaust manifold, an air heating tube fixed

in the said manifold, a hollow distributor valve adapted to receive hot air, cold air and fuel mixture through separate inlets leading thereto, a carburetor, an inlet and an outlet pipe to said carburetor communicating with said tube and said distributor valve respectively, said valve having a common outlet for its inlets, and means for manually operating said valve. 70

2. A charge-forming device comprising an exhaust manifold, a shell mounted on said exhaust manifold to leave a space between the top of said manifold and said shell, a hot air outlet opening at one side thereof, a mixture valve having a hot air opening adapted 75 to communicate with the hot air outlet, a tube leading from the space in the shell through the upper wall of the exhaust manifold and leading rearwardly and out near the rear bottom wall of the manifold, a carburetor, said carburetor having an inlet and outlet, a communication between the carburetor and said valve, a communication between said tube and the carburetor intake, said valve being provided with a cold air 80 inlet and having a discharge opening, and an intake manifold communicating with the valve discharge opening. 85

3. In a charge-forming device, a valve housing formed with a hot air inlet, a cold air inlet, a fuel mixture inlet and an explosive mixture outlet; a cylinder mounted within said valve housing and provided with openings to register with the openings in the housing, the hot air opening being an elongated slot on the side of the said housing, the elongation being on a line with the axis of the cylinder, a rectangular cold air opening, its longest dimension in line with the axis of the cylinder, a fuel mixture inlet 90 opening in the form of elongated slot traversing the circumference of the cylinder, and a substantially square opening in said cylinder serving as a common outlet. 95

4. In a charge-forming device, a valve housing having openings, a cylinder floatably and rotatably mounted in said housing and formed with openings adapted to register with the openings in the housing; the cylinder openings comprising an elongated cold air opening, a fuel mixture inlet opening, an explosive mixture outlet opening and a hot air opening of a distorted hexagonal shape and having a side edge making an obtuse angle that will by rotation of the cylinder 100 gradually enlarge a housing opening and having its other side formed with an obtuse angle pointing in the opposition direction and adapted to gradually restrict and close one of the housing openings and also gradually uncovering another of the housing openings while the first named opening is being restricted. 115

5. In a charge-forming device a valve housing having openings, a cylinder float- 120

ably and rotatably mounted in said housing and formed with openings adapted to register with the openings in the housing; the cylinder openings, a fuel mixture inlet opening, an explosive mixture outlet opening and a hot air opening of a distorted hexagonal shape and having a side edge making an obtuse angle that will by rotation gradually enlarge one of the housing openings and 10 its other side having an obtuse angle pointing in the opposite direction and adapted to gradually restrict and close the opening and also gradually uncovering another opening while the first named opening is being restricted and by rotating the cylinder still further completes a full opening of the last named opening.

6. In a charge forming device, a valve housing formed with a hot air inlet, a cold 20 air inlet, a fuel mixture inlet, and an explosive mixture outlet; a cylinder in said housing, said hot air and cold air inlets being elongated lengthwise of the cylinder, the fuel mixture inlet being elongated circumferentially of the cylinder, said housing being also formed with an outlet; said cylinder floatably and rotatably mounted and formed with an air opening, a fuel mixture inlet opening, and an explosive mixture outlet opening, said openings adapted 30 to register with the inlets and outlet in said housing, and disposed so that on partial rotation of the cylinder the hot air inlet will be restricted and the cold air inlet 35 partly open, a fuel inlet and exhaust outlet will be partly open, and whereby when the cylinder is further rotated the hot air inlet will be closed, and the cold air inlet, fuel mixture inlet, and the exhaust outlet will 40 be fully opened.

7. In a charge forming device, the combination of a carburetor, an exhaust manifold, an intake manifold, a rotary valve, a passage controlled by said valve leading to the intake manifold, a communication between said carburetor and said passage controlled by said valve, air heating means, means controlled by said valve for delivering heated air to said passage from said air heating means, and means controlled by said valve for delivering cool air to said passage.

8. In a charge forming device, the combi-

nation of a carburetor, an exhaust manifold, an intake manifold, a rotary valve, a passage controlled by said valve leading to the intake manifold, a communication between said carburetor and said passage controlled by said valve, air heating means, means controlled by said valve for delivering heated air to said passage from said air heating means, and means controlled by said valve for delivering cool air to said passage said valve adapted to vary the proportions of the heated air and the cool air delivered to said passage.

9. In a charge forming device, the combination of a carburetor, an exhaust manifold, an intake manifold, a rotary valve, a passage controlled by said valve leading to the intake manifold, a communication between said carburetor and said passage controlled by said valve, air heating means, means controlled by said valve for delivering heated air to said passage from said air heating means, and means controlled by said valve for delivering cool air to said passage said valve adapted to vary the proportions of the heated air and the cool air delivered to said passage and to vary the communication between the carburetor and the passage coincident with the variation of the heated air and cool air delivered to the passage.

10. In a charge forming device, the combination of a carburetor, an exhaust manifold, an intake manifold, a rotary valve, a passage controlled by said valve leading to the intake manifold, a communication between said carburetor and said passage controlled by said valve, air heating means, means controlled by said valve for delivering heated air to said passage from said air heating means, and means controlled by said valve for delivering cool air to said passage said valve adapted to vary the proportions of the heated air and the cool air delivered to said passage and to vary the communication between the carburetor and the passage coincident with the variation of the heated air and cool air delivered to the passage.

CARL H. HALLAUER.
